UNITED STATES PATENT OFFICE.

WILLIAM L. DURAND, OF NEW YORK, N. Y.

FOUNTAIN-PEN.

1,145,472.

Specification of Letters Patent.

Patented July 6, 1915.

Application filed April 21, 1915. Serial No. 22,754.

To all whom it may concern:

Be it known that I, WILLIAM L. DURAND, a citizen of the United States of America, residing at the borough of Brooklyn, city of New York, in the county of Kings and State of New York, have invented certain new and useful Improvements in Fountain-Pens, of which the following is a specification, reference being had to the accompanying drawings.

This invention relates to improvements in fountain-pens; and an object of this invention is to provide a fountain-pen with means for preventing, during the filling of the reservoir or barrel of the pen, the squirting out of the ink due to the sudden escape or outflow of the air entrapped beneath the ink. It has been found that, when the ink is allowed to flow into the font or reservoir of a fountain-pen, as the same has heretofore been constructed, the air in the reservoir is liable to be caught beneath the ink; and, upon escaping, the entrapped air will carry with it some of the ink, so that the ink appears to squirt out of the reservoir or barrel and is liable to soil the fingers of the one who is filling the barrel with ink.

In the drawings illustrating the principle of this invention and the best mode now known to me of applying that principle, Figure 1 is an elevation of a fountain-pen embodying this invention; Fig. 2 is a longitudinal section through the reservoir or barrel of the fountain-pen, the section being taken on the line II—II of Fig. 3; and Fig. 3 is a section on the line III—III of Fig. 1.

The reservoir, barrel or font *a* of the pen is formed at one end with interior screw-threads *b* and into this end there is screwed the nozzle or plug *c* which carries the nib *d*. The inside of the barrel *a* is formed with a pair of diametrically-opposite lengthwise-extending grooves *e*; and, into these grooves, there is slipped a partition wall *f* which divides the interior space of the barrel into two parts *g*, *h*. However, the grooves *e* do not extend as far as the closed end *i* of the barrel but stop short thereof, thereby leaving a space *j* at that end of the wall *f*. The two channels or compartments *g*, *h*, communi-

cate with each other through the space *j*, so that the compartment *g*, space *j* and compartment *h* form in effect a U-tube.

When it is desired to fill the barrel *a* with ink, the ink-dropper is held so that it will discharge the ink into either the arm *g* or the arm *h* of this U-tube; and the ink flowing down one arm will rise in the other arm, thereby forcing the air outwardly. This construction prevents the accumulation or entrapping of air underneath the ink and the soiling of the fingers which results from such entrapped air's escaping suddenly from the barrel and carrying with it a part of the ink.

To provide for the escape of the air, when the barrel is partly filled, I form the partition *f* with slots *k*; hence, when the ink is dropped into one leg (or arm) of the partly filled U-tube, the air will flow from one leg (or arm) to the other leg (or arm) thereof and escape, while the ink will flow, as before, down one leg (or arm) and up the other.

I claim:

1. A fountain-pen barrel having a lengthwise-extending partition which divides the barrel into two parts which are in communication with each other at the permanently-closed end of the barrel and form the legs of a U-tube; the ink in filling the barrel flowing down one leg and up the other leg of the U-tube, thereby permitting the free escape of air from the barrel.

2. A fountain-pen barrel having a lengthwise-extending slotted partition which divides the barrel into two parts which are in communication with each other at the permanently-closed end of the barrel and form the legs of a U-tube; the ink in filling the barrel flowing down one leg and up the other leg of the U-tube, thereby permitting the free escape of air from the barrel.

Signed at the borough of Manhattan, city, county and State of New York, this 17th day of April, A. D. 1915, in the presence of the two undersigned witnesses.

WILLIAM L. DURAND.
